US00D843978S

(12) **United States Design Patent** (10) **Patent No.:** **US D843,978 S**
(45) **Date of Patent:** **** Mar. 26, 2019**

(54) **BROADCASTING DEVICE**

(71) Applicant: **InMusic Brands, Inc.**, Cumberland, RI (US)

(72) Inventors: **Scott Puckett**, Pawtucket, RI (US); **Paul Jenkins**, North Providence, RI (US); **Carl Barton**, Mapleville, RI (US); **Gregory Holmes**, Lincoln, RI (US); **Daniel Montecalvo**, Warren, OH (US); **John O'Donnell**, Fort Lauderdale, FL (US); **Mark Frederick**, Bristol, RI (US)

(73) Assignee: **inMusic Brands, Inc.**, Cumberland, RI (US)

(**) Term: **15 Years**

(21) Appl. No.: **29/609,507**

(22) Filed: **Jun. 30, 2017**

(51) **LOC (11) Cl.** **14-01**

(52) **U.S. Cl.**

USPC **D14/227**

(57) **CLAIM**

The ornamental design for a broadcasting device, as shown and described.

DESCRIPTION

FIG. 1 is a front perspective view of a broadcasting device showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof; and,

FIG. 7 is a bottom view thereof.

The broken lines showing are for the purposes of illustrating the environment of the article only and form no part of the claimed design.

1 Claim, 7 Drawing Sheets
